UNITED STATES PATENT OFFICE.

ERNEST J. SHAFFER, OF TULSA, OKLAHOMA.

PICK-UP IRON.

Application filed January 14, 1927. Serial No. 161,222.

Sometimes in the working of several relatively shallow oil wells that are grouped within a radius of a half to three quarters of a mile, a power plant that is located at 5 a central position with respect to said wells is used for pumping the several wells. This power plant involves a suitably driven vertical shaft which carries a number of eccentrics that are equipped with the usual eccentric straps, and arms which are attached to these straps project out through guides and are fitted at their outer ends with clevises to which may be attached cables that lead to the respective wells. In the set up of the 10 apparatus, a clevis or the like is attached to the end of each cable, and then, by means of what is known as a pick-up iron, the clevis on the end of the cable is attached to the clevis on the end of the corresponding eccentric arm. The distance between the clevises on the cables and arms, when all connections are taut, is an approximately fixed distance, but through stretching of the cables or from other causes this distance may vary slightly. 15

20 The present invention relates to an improved pick-up iron for connecting the ends of the eccentric arms and cables in outfits of the above character, and its primary purpose is to provide a device of this nature that has hooks on one side that are spaced apart a distance substantially equal to the approximate normal distance between the clevises of the eccentric arms and cables, and on the opposite side hooks that are spaced apart a lesser distance so that by reversing 25 the iron the stretching of the cables or other such irregularity may be compensated for.

30 Further objects are to provide a device of the aforesaid character which is very substantial and which is designed to afford convenience of handling and protection to the user's fingers and hand when applying the device to the working lines.

35 The foregoing objects are attained in a pick-up iron of the form illustrated in the accompanying drawing wherein Fig. 1 is an elevational view of the iron, and Fig. 2 a central transverse section through the same on the line 2—2 of Fig. 1.

40 45 50 The device consists of a body portion 1, having hooks 2 projecting from its opposite ends in one direction from the longitudinal axis of the body, and hooks 3 projecting in the other directions from its opposite ends.

The hooks 2 are spaced apart to accommodate the normal spacing of the clevises in a working line, while the hooks 3 are set closer together to compensate for elongation of the line. 55

Depressions 5 are formed on opposite sides 60 of the central portion of the body 1, giving to said body a form that is substantially I-shaped in cross section, thereby providing flanges 6 that are rounded so as to constitute comfortable hand grips, the device being 65 adapted to be held by the grip or flange on one side while applying the hooks that project from the opposite side of the body to the clevises of the working line. The flange 6 opposite the one by which the device is being 70 held, and the hooks on the same side with the grip that is being used to hold the device, serve to protect the user's hand from injury as he engages the hook, first with the clevis on the end of the cable, and then with 75 the clevis on the end of the eccentric arm as the latter reaches the outward limit of its movement. Having to perform this operation while the power plant is working 80 is more or less dangerous unless the user's hand is protected as above explained. Therefore it will be seen that, in addition to compensating for the stretching of the working line, etc., the double hook has the 85 second purpose of shielding the hand, and accordingly the invention is not limited, in its broadest phase, to the different spacing of the opposed hooks.

The web 7 between the flanges 6 imparts ample strength to the body portion to withstand the strains to which it is subjected, and enables the user to control the movements of the relatively heavy iron more accurately, by providing a purchase for the ends of the thumb and fingers. 90 95

Having thus described my invention, what I claim is:—

1. A pick-up iron comprising a body portion from each end of which hooks extend in opposite directions, the hooks occurring on one side of the longitudinal axis of the body portion being spaced further apart than those occurring on the other side of said axis. 100
2. A pick-up iron comprising a body portion from each end of which hooks extend in opposite directions, all of said hooks and the body portion being in a substantially common plane, the iron being symmetrical on 105

opposite sides of its central transverse axis.

3. A pick-up iron comprising a body portion from each end of which hooks extend in opposite directions, all of said hooks and

5 the body portion being in a substantially common plane, and the body portion having depressions in its opposite faces.

4. A pick-up iron comprising a body portion from each end of which hooks extend in opposite directions, the body portion being 10 substantially I-shaped in cross section.

In testimony whereof, I hereunto affix my signature.

ERNEST J. SHAFFER.
